Attorney

UNITED STATES PATENT OFFICE.

ELLA M. ROBERTS, OF CHICAGO, ILLINOIS.

POWDER RECEPTACLE.

Application filed March 29, 1923. Serial No. 628,495.

To all whom it may concern:

Be it known that I, ELLA M. ROBERTS, a citizen of the United States, residing at Chicago, in the county of Cook and State of Illinois, have invented certain new and useful Improvements in Powder Receptacles, of which the following is a specification.

This invention relates to improvements in powder receptacles.

The primary object of this invention is the provision of a relatively simple and compact type of powder box or receptacle, embodying novel means for supporting a puff therein.

A further object of this invention is the provision of a novel lid or closure member for powder receptacles, embodying novel constructions to permit a powder puff to be detachably associated therewith in such manner that the puff may be suspended where the same may be easily placed or detached as desired.

Other objects and advantages of this invention will be apparent during the course of the following detailed description.

In the accompanying drawing, forming a part of this specification, and wherein similar reference characters designate corresponding parts throughout the several views,

Figure 1 is a side elevation of the improved powder receptacle.

Figure 2 is a transverse cross sectional view taken through the improved powder receptacle.

Figure 3 is a bottom plan view of the closure member or lid of the improved powder receptacle, showing novel construction thereof which will permit a powder puff to be detachably associated therewith.

In the drawing, wherein for the purpose of illustration is shown but the preferred embodiment of this invention, the letter A may generally designate the improved receptacle which may include the container portion B; closure member or lid C; and puff D.

The receptacle may be constructed of any approved material, which may vary according to the quality of container desired. It may be formed of carved wood, porcelain, ivory, pyroxyline, silver, or other material. The container B thereof may be of any approved formation, although it is preferred that the same be of artistic outline, prefer-

ably including a relatively narrow flat bottom 10, from which the concavo-convex walls 11 may extend, outwardly and upwardly therefrom. An inwardly depending flange 12 may be provided, extending downwardly into the compartment 13 provided by the main container portion B, and which defines an opening 14, the diameter of which is considerably less than the maximum diameter of the container portion B, as defined by the side walls 11 thereof. Within the compartment 13, the powder or other material 16, is of course placed.

Referring to the closure member or lid C, the same is of novel construction; preferably being circular in plan view, and of less diameter than the maximum diameter of the container B. It includes the top wall portion 20, axially of which the upwardly extending finger engaging knob 21 is provided, as a means to facilitate handling of said closure member. The same includes the concavo-convex side walls 23, which extend in such relation to the top wall 20 as to provide an annular seating surface 25, in facing relation with the inner surface of the top wall 20. This closure member 20 preferably provides the annular seating flange 27, extending outwardly from the inside of the closure member C and immediately adjacent the seating surface 25, which is of diameter to snugly, although detachably, seat within the opening 14 defined by the container portion B.

A flat horizontal supporting wall or shelf 30 is preferably integrally formed with the closure member C, extending substantially in the same plane, and flush with the annular seating surface 25. This wall 30 is substantially crescent shaped and provides a concaved marginal edge 40, which is in facing relation with a part of the concaved inner periphery 41 defined by the flange 27, thus providing an opening 42 through which the puff D may be inserted or extracted with respect to the closure member C.

The powder puff D may be of any approved type, including the flexible body 45 of any approved material, which is of course compressible, and may have the finger engaging knob 46 extending axially therefrom.

In the cooperation of parts, the puff D is of a diameter sufficient to permit the same

to occupy the compartment 47 defined by the closure member C, so that the outer edge portions thereof may rest upon the annular supporting surface 25 of the closure member C adjacent the opening 42. The main supporting action is, however, effected by the crescent shaped supporting shelf 30, as can readily be understood. While the opening 42 is comparatively small, in fact, being smaller than the area defined by the crescent shaped wall 30, it is yet sufficient to permit the ready insertion or detachment of the powder puff D with respect to the closure member C. In position, should the powder puff D be provided with the engaging knob 46, the same is adapted to lie in abutting relation with the concaved edge 40. From the foregoing description of this invention it is obvious that a powder receptacle has been provided, which is very compact, and which is particularly efficient in that it provides structure for the reception of a powder puff, so that the same may be suspended free of the powder and only dipped into the powder as desired. This structure for the support of the puff enables a person to readily insert the same into its proper compartment, with ease.

Various changes in the shape, size and arrangement of parts may be made to the form of invention herein shown and described, without departing from the spirit of the invention or the scope of the claims.

I claim:

- 35 1. As an article of manufacture, a lid for powder boxes formed to provide a top wall, concavo-convex side walls annularly extending about said top wall, a depending annular neck forming flange leading from the lower edge of the side wall and a crescent shaped bottom wall at the junction of

the neck and side wall and providing a pocket intermediate the top wall and the side walls, said crescent shaped wall providing a concaved marginal wall in spaced relation with a part of the side walls of said lid to provide an opening into said lid.

2. As an article of manufacture, a lid for powder boxes having a top wall, an annular depending side wall having its lower portion extending inwardly to provide a supporting ledge and terminating in a depending annular neck forming flange, and a shelf at the junction of the neck and supporting ledge extending partially across the space enclosed by the neck and leaving an open space through which a powder puff may be passed into the lid and supported upon the ledge and shelf.

3. In a powder receptacle, the combination of a main container, and a hollow lid for said container having an open depending neck and a supporting shelf extending inwardly from the upper end of the neck partially across the space enclosed thereby and providing a puff support, and a puff adapted to be passed into the hollow lid through the neck and rest upon the shelf.

4. A receptacle of the class described comprising a container open at its upper end and having an inwardly extending depending flange about the opening, a hollow lid providing a compartment therein and having a depending open neck fitting into the opening of the container in frictional engagement with the annular flange, and a shelf partially closing the upper end of the neck whereby a puff may be passed into the compartment of the lid through the neck and rest upon the shelf.

ELLA M. ROBERTS.
